UNITED STATES PATENT OFFICE.

CYRUS H. SINCLAIR, OF CHICAGO, ILLINOIS, ASSIGNOR OF TWO-THIRDS TO
GEORGE L. McCURDY AND BURT C. LINDLEY, OF SAME PLACE.

POR TABLE HOIST.

SPECIFICATION forming part of Letters Patent No. 658,810, dated October 2, 1900.

Application filed April 2, 1900. Serial No. 11,063. (No model.)

To all whom it may concern:

Be it known that I, CYRUS H. SINCLAIR, a citizen of the United States, residing at Chicago, in the county of Cook and State of Illinois, have invented certain new and useful Improvements in Portable Hoists, of which the following is a full, clear, and exact specification.

My invention relates more particularly to portable hoists designed for unloading vessels; and it has for its primary object to provide a simple and compact portable hoist capable of being readily folded when not in use and as readily set up on the deck of the vessel or other surface where it is to be used and securely held and braced while the cargo is being elevated from the hold and dumped into the lighter or other desired place.

Another object of my invention is to provide improved and simple means whereby the inclination of the runway upon which the bucket-carrying trolley travels may be varied at will to suit the varying inclinations of the deck or other surface on which the hoist is supported.

With these ends in view my invention consists in certain features of novelty in the construction, combination, and arrangement of parts by which the said objects and certain other objects hereinafter appearing are attained, all as fully described with reference to the accompanying drawings, and more particularly pointed out in the claims.

In the said drawings, Figure 1 is a vertical longitudinal sectional view of my improved hoist, showing the same supported over the hatchway of a vessel for unloading the same onto the wharf or pier. Fig. 2 is an enlarged detail sectional view showing the bucket or holder in the act of releasing itself from the trolley. Fig. 2^a is an enlarged transverse sectional view of the runway and trolley. Fig. 2^b is a detail view of a joint for connecting the standards to a brace-rod hereinafter described. Fig. 3 is a vertical transverse section looking from the left-hand side as viewed in Fig. 1, and Fig. 4 is a plan view.

I have shown my invention in connection with a boat or vessel for unloading the same as an example of the many uses to which the invention may be put, this, however, being

its greatest field of usefulness at present known to me, owing to the great need of a suitable hoist that may be folded in a compact form and stowed away in the very limited space that could ordinarily be spared on shipboard for an article of this kind.

1 represents a runway or track, which preferably consists of an I-beam, the lower flanges of which serve as supports or tracks for the rollers 2 of a trolley 3, whose rollers are journaled on suitable pintles projecting inwardly from side plates 4, arranged on each side of the I-beam 1, as better shown in Fig. 2^a. The trolley 3 is provided with a hook 5 or other support by means of which a bucket 6 or other holder for containing or carrying the material to be hoisted from the hold of the vessel and having a bail 7 or other equivalent device may be supported from the trolley when it is desired to convey the bucket to the end of the runway and dump the material overboard and detached from the trolley when it is desired to lower the bucket into the hold to be again filled. The bail 7 may be provided with any suitable detachable device for supporting it upon the hook 5. I have shown it provided with a simple link 8, which engages over the hook 5 when the bail is not otherwise supported, but when the bail is lifted above the hook 5 the link 8 will disengage therefrom. The upper end of the bail is attached to a chain or cable 9, which runs over a sheave or pulley 10, supported by a bracket 11 from the under side of the beam 1, the other end of the chain passing around a winch or drum 12, operated by a steam-engine or in any other suitable way.

At or near one end of the beam 1 is secured a pair of inclined standards, which are telescopic or expandable and support the runway upon the deck 13 in such a way that the inclination of the runway may be varied at will to suit the varying inclinations of the deck or other surface on which the apparatus is to be supported. Each of these standards preferably consists of an upper tubular member 14 and a lower telescopic member 15, inserted in the tubular member 14 and held at the desired adjustment by means of set-screws 16 or other suitable devices. The upper ends of the tubular members 14 are provided with

perforated ears 17 and the upper side of the runway or beam 1 with a perforated lug 18, and through these ears 17 and the lug 18 passes a removable bolt or pin 19, whereby the runway 1 may not only be rotated or inclined with reference to the standards 14 15, but the standards may be readily detached from the runway and folded together therewith in a compact form when it is desired to stow the apparatus away. The lower ends of the members 15 are pointed, so as to dig into the deck and prevent the inclined standards from slipping, and each of the members 14 at or near its lower end is provided with a collar 20, which serves as a support for a perforated lug 21, through which passes a bolt 22, having a hook 23 on its lower end, which passes downwardly through the hatch 24 and engages with the inside of the deck, as clearly shown in Fig. 3, the upper end of the bolt 22 having a nut 25, whereby the grip of the hook 23 may be tightened and the standards 14 15 thus firmly clamped to the deck and held against both vertical and lateral movement at their lower ends. The upper end of each of the standards 14 is held against oscillation by a pair of guy-rods or cables 26, both secured at their upper ends to a collar 27, adjustably clamped to the tubular member 14 by set-screw 28, while the lower end of each of the guys 26 is hooked to an eye-bolt 29, secured in the deck, and is also provided with a turnbuckle 30, whereby the guy may be tightened.

35 By the means described it will be seen that one end of the runway may be firmly supported over the hatch and held against undue vibration in all directions. In order to support the other end of the runway, I provide the same with a pair of standards similar to those already described and preferably consisting of tubular members 31, receiving the pointed members 32, clamped therein to the desired adjustment by set-screws 33, 45 while the upper ends of the tubular members 31 are secured to the runway by means similar to that already described with reference to the other standards—to wit, a perforated lug 34, formed on or secured to the upper side of the I-beam 1, and perforated ears 35 on the members 31 and through which ears a bolt or pin 36 passes. The lower ends of the standards 31 32 are held from spreading by means of a brace-rod 37, detachably secured to adjustable collars 38 on the members 31 by means of perforated ears 39, formed on the collars 38, and pins 40, passing through said ears and the ends of the brace-rod 37.

50 In the use of the apparatus the runway 1 is supported transversely of the ship or vessel, if to be used on a ship or vessel, with the pulley or sheave 10 substantially over the hatch and the lower end of the runway projecting over the side of the vessel. The bucket 6 or other holder may then be lowered into the hold and drawn up by hand or by

the steam-winches, as described, until the link 8 is at a sufficient elevation to enable an operator who may stand upon a detachable platform 41, secured by suitable collars 42 to the members 14 31, to place the link over and in engagement with the hook 5 of the trolley, whereupon, the cable being paid out, the trolley runs down the track or runway and suspends the bucket or holder over the side of the vessel, whence it may be caused to dump in any suitable or well-known way, the lower end of the I-beam 1 being also flanged vertically, as shown at 1^a, to prevent the trolley 80 from falling off. The bucket dumped, the trolley is drawn back into the upper end of the runway until the upward lift on the bail 7 disengages the link 8 from the hook 5, or, as before explained, such bail may be disengaged from the hook 5 by any of the improved hook devices well known in the art, and when once disengaged the bucket is again lowered into the hold, and so on.

When the device is not needed for use, the standard members may be telescoped one within another, thus reducing their length, and entirely detached from the I-beam 1, as also from the platform 41 and clamp-bolts 22, and the parts thus separated folded lengthwise in a neat and compact bundle.

Having thus described my invention, what I claim as new, and desire to secure by Letters Patent, is—

1. In a portable hoist the combination of a track or runway, a pair of inclined standards detachably secured to said runway, guys for holding the upper ends of said standards against oscillation longitudinally of said runway, bolts secured to said standards and having means of attachment to the surface upon which said standards are supported for holding the lower ends of said standards against movement, said standards serving to support said runway at one point, means for supporting said runway at another point, a trolley on said runway, a holder for the material to be hoisted adapted to be connected to said trolley and means for raising and lowering said holder, substantially as set forth.

2. In a portable hoist the combination with the vessel-deck having a hatch, of a runway, a pair of inclined standards detachably secured to said runway, bolts having hooks adapted to pass through the hatch and engage under the edge thereof, means for adjustably securing said bolts to said standards, a trolley on said runway, a holder for the material to be hoisted adapted to be supported from said trolley and means for raising and lowering said holder, substantially as set forth.

3. In a portable hoist the combination of a runway, a pair of inclined standards detachably secured to said runway at or near each end thereof, a brace secured to the standards of one of said pairs for preventing them from spreading, guys for preventing the standards of the other of said pairs from oscillating at their upper ends lengthwise of said runway,

bolts adapted to be secured to the surface on which said standards are supported and to the last said standards for preventing the latter from spreading, a trolley on said runway, 5 a holder for the material to be hoisted adapted to be attached to said trolley and means for raising and lowering said holder, substantially as set forth.

4. In a portable hoist the combination of a runway consisting of a beam having flanges, a trolley supported by said flanges, perforated lugs formed on said beam, standards for supporting said beam having perforated ears, bolts or pins passing through said lugs and 15 ears, means for bracing said standards against oscillation, a holder for the material to be elevated adapted to be secured to said trolley and means for raising and lowering said holder, substantially as set forth.

5. In a portable hoist the combination of a beam having a flange, a trolley supported by and running on said flange, inclined standards detachably pivoted to said beam and having extensible portions, collars adjustably 25 secured on said standards, bolts provided

with hooks, adjustably secured to said collars, a holder for the material to be hoisted adapted to be attached to said trolley and means for raising and lowering said holder, substantially as set forth. 30

6. In a portable hoist the combination of the beam 1 having the perforated lugs 18 34, the trolley having rollers engaging with said beam, a holder adapted to be secured to said trolley, means for raising and lowering said 35 holder comprising a sheave 10 secured to said beam, extensible standards pivotally secured to said lugs 18 34, the bolts 22 secured to one pair of said standards and having hooks 23, adjustable guys 26 secured to one pair of said standards near their upper ends and the brace-rod 37 detachably secured to the other pair of said standards for preventing the same from spreading, substantially as set forth. 40
